SHIPPING CRATE AND CLOSURE THEREFOR

Filed March 6, 1924

Inventor

George H. Hamp

By

Kubert E. Becker Attorney

UNITED STATES PATENT OFFICE.

GEORGE H. HAMP, OF DECATUR, ILLINOIS.

SHIPPING CRATE AND CLOSURE THEREFOR.

Application filed March 6, 1924. Serial No. 697,246.

To all whom it may concern:

Be it known that I, GEORGE H. HAMP, a citizen of the United States of America, and a resident of Decatur, county of Macon, 5 State of Illinois, have invented certain new and useful Improvements in and Relating to Shipping Crates and Closures Therefor, of which the following is a specification.

This invention relates to certain improvements in shipping crates and closures therefor; and the nature and objects of the invention will be readily recognized and understood by those skilled in the art involved in the light of the following explanation and detailed description of the accompanying drawings illustrating what I at present consider to be the preferred embodiments or mechanical expressions of my invention from among various other forms, arrangements, combinations and constructions of 15 which the invention is capable within the spirit and scope thereof.

With the conventional types of shipping crates or boxes, such for example as the well known wood egg crates or cases in universal use for packing and shipping eggs, the closure or top for such a crate is generally formed of a relatively thin wood board or boards placed across and over the open upper side of the crate and fixed in position closing the same by nailing or otherwise fixing the ends of the closure to the opposite end walls of the crate. In order to open a wood crate so closed it is necessary to remove the cover or closure by detaching the fixed attached ends of the board or boards forming the closure, from the end walls of the crate. Where the crate closure or cover is nailed to the crate in accordance with the prevailing practice, the cover is usually removed to open the crate, by prying or forcing the nailed ends thereof from attachment to the crate, with the possibility of resulting damage through the breaking or splitting of the board or boards forming the cover, so as to render the cover unfit for further use. Damage is likewise frequently caused in nailing the ends of the closure or cover to the crate end walls with

the result that the cover or closure is weakened and liable to break or become detached when subjected to blows and strains in use. Further, the operations of nailing a crate cover or closure, and of removing the same to open a crate, call for the expenditure of 55 a considerable amount of time and labor which is a decided disadvantage attendant this prevailing method of attaching and removing the covers to and from such general type of shipping crate.

Therefore, one of the main and fundamental objects of the present invention is to eliminate the necessity of nailing or similarly fixing the covers or closures to wood and such like shipping crates with the attendant disadvantages in attaching and removing the same to and from a crate, by providing for the ready and quick attachment and removal of a closure or cover from a shipping crate without injury or damage to 70 the cover or the crate so that a cover can be repeatedly used.

Another object of the invention is to provide a metal end clip or cleat for the ends of wood closures or covers for shipping crates or the like, which is so formed and mounted that a cover can be firmly secured in position on and closing a crate without the use of nails or similar fastening means.

Another object of the invention is to provide a sheet metal or the like material clip or cleat for mounting on the ends of wood closures or covers for shipping crates, which is mounted attached position on the ends of a cover form binding and bracing elements 85 therefor guarding the cover against damage, and which further provide means for attaching and securing a cover in position on and closing a crate.

A further object of the invention is to 90 provide an inexpensive and simple metal clip or cleat capable of production in quantities, and adapted for attachment on and over the ends of the conventional or other types of closure or cover for a shipping 95 crate, and which in attached position on a cover provide elements by which the cover can be detachably secured to the crate in

position closing the same without the necessity of nailing or similarly securing the cover to the crate.

With the foregoing general objects, and 5 certain other objects and results in view, which other objects and results will be readily apparent to those skilled in the art from the following description, the invention consists in certain novel features in construction and in combination and arrangement 10 of elements, as will be more fully and particularly referred to and specified herein-after.

Referring to the accompanying drawings, 15 wherein similar reference characters designate corresponding parts:

Fig. 1 is a perspective view of a wood shipping crate and cover therefor, of the more or less conventional egg crate type, with the 20 wood cover equipped with the end clips or cleats of the invention and in attached position on and closing the crate.

Fig. 2, is a vertical, longitudinal section 25 through the crate cover and end clips or cleats of the invention with the cover in closed position on a crate and the end cleats thereof attached to the end walls of the crate, and securing the cover on and to the crate, portions only of the crate end walls being 30 shown.

Fig. 3, is a detail perspective view of an 35 outer end portion of an end clip or cleat in attached position on a wood cover, and showing the manner of securing the cleat over the outer side edge of the cover, a portion only of which is shown.

In Fig. 1 of the accompanying drawings 40 a wood egg crate of more or less conventional type familiar to those skilled in this art is shown, and includes the usual end walls 10, side walls 11, bottom wall (not shown) and closure or cover 12. The end walls 10 are provided with the upper and lower transverse braces or wood cleats 14 and 15 nailed thereacross on the exterior 45 thereof in the usual manner. The closure or cover 12 is formed in the present instance of a single wood board, and according to the prevailing methods in general use is secured in position on and closing the crate by nailing the ends thereof to the upper 50 transverse wood cleats 14 on the opposite end walls 10, as hereinbefore referred to. However, frequently a wood crate cover is 55 formed of two or more boards secured together by transverse wood cleats, as will be readily recognized by those familiar with shipping crates, and therefore not necessary of illustration herewith. Hence, it is not intended by the illustrated example to restrict 60 the use of the invention to a single piece wood closure or cover, as it is equally applicable and obtains certain decided advantages in use with a cover formed of several 65 boards.

In accordance with the invention, the wood crate cover 12 is provided with the metal clips or cleats 20 attached over and extending across the opposite ends thereof, respectively. In the disclosed mechanical 70 expression of the invention, each clip or cleat 20 is formed of a single piece or blank of sheet metal of a length substantially the same as the width of the crate cover 12, which blank is bent or folded over upon 75 itself along a longitudinal line to provide a flange 21 formed of two plies for a portion of its width or depth. The outer ply of flange 21 extends a distance beyond the inner ply thereof, and the inner and outer plies of the flange are bent at an angle to the plane of flange 21 to form the spaced flanges 22 and 23 extending laterally from one side of the flange 21, as particularly 80 shown in Fig. 2 of the accompanying drawings. Each of the flanges 22 and 23 is formed at its opposite ends with the ears or tabs 24 adjacent the outer or free longitudinal edges thereof, respectively, extending along a portion of the flange side edges and terminating a distance from the flange 21 (see Fig. 3 of the drawings particularly). Intermediate the ends of the flange 21 a bore or opening 25 (see Fig. 2) is formed 85 through the multiple portion thereof and the portion of the flange adjacent the bore 25 is bent or pressed at opposite sides of the flange so as to in effect offset the bore 25 from the plane of the flange, in the present instance the flange on the outer side of the bore is bent in a direction away from the lateral spaced flanges 22 and 23 (see Fig. 90 2), for a purpose referred to and explained hereinafter.

A sheet metal clip or cleat 20 so formed 95 is mounted on and attached over and to the end of a crate closure or cover such as the cover 12, by the spaced flanges 22 and 23. The flanges 22 and 23 are fitted over the end portion of the cover 12 with the forward edge thereof abutting or bearing 100 against the portion of the outer ply of flange 21 extending across and between the flanges 22 and 23, so that these flanges of the cleat 20 form in effect a socket to receive the cover end with the flanges extending inwardly a distance over the upper and lower sides of the cover. The cleat 20 is mounted 105 on the end of the crate cover with the flange 21 depending downwardly therefrom, and is fixed or secured in position on the cover by means of nails, screws, bolts or the like passing through the cover and the flanges 22 and 23, in the example illustrated 110 the nails 26 are employed for this purpose, as shown in Fig. 2. If desired or found expedient suitable alined bores can be formed in the flanges 22 and 23 to receive the nails 26 or other fastening means employed. After a cleat 20 is fixed in position 115 120 125 130 135

- over and extending across the end of a closure, as above described, the opposite end portions of the flanges forming the ears or tabs 24 are bent inwardly toward each other
- 5 to position bearing and binding against the side edges of the cover respectively adjacent thereto. This position of the portions forming the tabs 24 is clearly shown in Fig. 3 of the drawings.
- 10 At this point attention is directed to the fact that the tabs or ears 24 of the flanges 22 and 23 can be formed by extended portions of the flanges, or can be formed by making the flanges slightly greater in length than the width of the cover to which applied and then bending or forcing the outer portions of the end overhang of the flanges inwardly against the cover side edge, as indicated in Fig. 3 of the drawings by
- 15 the portion of the flanges adjacent the flange 21 extending a distance beyond the side edge of the cover 12.
- 20 In the form of crate illustrated as an example herewith, the cover 12 thereof is provided at both ends with one of the metal clips or cleats 20 extending completely thereover and thereacross, with the flanges 21 thereof, respectively, depending downwardly a distance below the cover 12. The
- 25 cover is placed in position on the crate over and closing the open side thereof, with the flanges 21 of the cleats 20 depending a distance over the transverse wood braces 14 at the upper ends of the opposite end walls 30 of the crate, the cover 12 being of a length slightly greater than the over-all length of the crate so that the flanges 21 fit over the transverse braces 14 (see Fig. 2).
- 35 The cover 12 is detachably secured in mounted position on and closing the crate through the medium of the opposite end depending flanges 21 of the cleats 20, respectively. In the instant example, the
- 40 crate is provided at each end thereof with a staple 16 secured in substantially horizontal position in the transverse braces 14 and extending outwardly a distance therefrom with the openings thereof below and in substantial vertical alinement respectively, with the bores 25 through the depending cleat flanges 21, as shown in Fig. 2 of the drawings. A length of wire or the like 27 is then threaded through the bore 25 of each cleat flange 21 and the staple 25 therebelow, and twisted together as shown in Fig. 2, to bind and firmly secure the flanges 21 to the staples 25, respectively, and thus tightly and securely attach the cover 12 in mounted position on and closing the crate. When it is desired to remove the cover, the wires 27 can either be untwisted or cut and the cover 12 thereby detached for removal from the crate. It will be here noted that due to the offset position, of the bores 25 with respect to the depending

flanges 21 of the cleats, that the wires 27 are readily threaded or passed therethrough and through the staples 16, respectively, which are in vertical alinement therewith.

In the foregoing manner through the medium of the metal end clips or cleats 20 attached on and over the opposite ends of the wood cover 12, this cover can be quickly secured and attached in position on and closing a crate by binding the depending flanges 21 to the staples 16 on the crate with wire or the like 27. The cover 12 can likewise be quickly removed to open the crate without possibility of injuring or damaging the cover, with the result that the cover can be repeatedly used for an indefinite period of time. The metal end cleats form braces which bind and protect the ends of the cover and prevent breakage or splitting thereof, while the portions 24 bent over the side edges of the cover further aid against splintering or splitting of the material forming the cover. With those covers, hereinbefore referred to, formed of several boards, the use of the metal cleats of the invention eliminates all cross members and braces and securely bind the boards in cover forming position.

In the illustrated example of the invention the cleats 20 are formed with a single bore 25 in flanges 21 for attaching the cleats to the crate, but the invention contemplates and includes the provision of two or more bores 25 through each cleat flange 21 for attachment to suitable elements, such as the staples 16, on the ends of a crate.

While the invention is disclosed herewith as applied to and in use with a wood crate and cover of the egg crate type, it will be readily apparent that the invention is likewise applicable to other types of crates, as well as containers and receptacles generally where similar closure conditions are encountered. Further, the principles and features of the invention as exemplified by the illustrated application thereof to a wood crate and cover, are capable of adaption and use with crates and receptacles of other materials, such as metal, and it is not desired therefore to confine the use of the invention to crates of the wood types.

It is also evident that various changes, variations, substitutions and modifications might be resorted to without departing from the spirit and scope of my invention, and hence, I do not wish to limit myself to the exact disclosures hereof.

Desiring to protect my invention in the broadest manner legally possible, what I claim is:

1. In a crate including end walls and a cover, an end cleat attached over and extending across an end of the cover, a fastening element on the adjacent end wall of the crate, and a detachable securing member

adapted to connect said cover end cleat and the fastening element on the crate end wall.

2. In a crate including end walls and a cover, an end cleat attached over and extending across an end of the cover, said cleat having a depending flange, a fastening element on the adjacent end wall of the crate, and a detachable securing member connecting the depending flange of said cover end cleat and the fastening element on the adjacent end wall of the crate.

3. In a crate including end walls and a cover, an end cleat attached over and extending across an end of the cover, said cleat having a depending flange formed with a bore therethrough, an apertured member on the adjacent end wall of the crate and disposed below the bore of said end cleat flange, and a detachable securing member extending through said flange bore and said apertured member on the adjacent end wall of the crate to secure the end of the crate cover in closed position on the crate.

4. In a crate including opposite end walls and a cover, an end cleat attached over and extending across each end of the cover, each cleat formed with a depending flange having a bore therethrough, and detachable securing members in said cleat flange bores for attachment to the adjacent end walls, respectively, of the crate to secure the cover in closed position.

5. In a crate including wood end walls and a wood cover, a metal cleat attached over and across an end of the cover and formed with a depending flange having a bore therethrough offset outwardly from the plane of the flange, and an apertured member mounted on the end wall of the crate below and vertically aligned with the bore of said cleat flange with the cover in closed position on the crate.

6. In a crate including end walls and a cover, a metal cleat fitted over an end of the cover and extending completely thereacross to form a bracing and guarding member therefor, said cleat provided with a flange depending below the cover, and a member mounted on an end wall of the crate for detachable connection with said depending cleat flange to secure the end of the cover to the crate.

7. In a crate including end walls and a cover, a metal cleat fitted over an end of the cover and extending thereacross and a distance beyond the opposite sides thereof with the extended ends bent inwardly against the opposite side edges, respectively, of the cover, and the said cleat formed with a depending flange for detachable connection with an end wall of the crate to secure the cover thereon.

8. In a crate including end walls and a cover, a metal cleat attached over an end of the cover and formed with a depending

flange having a bore therethrough offset outwardly from the plane of the flange, and a staple secured on an end wall of the crate in position below and in vertical alinement with said offset aperture of the cleat flange when the cover is in closed position on the crate.

9. A crate including end walls and a cover, a cleat fitting over and extending across each end of the cover and formed with a portion depending therefrom on the exterior of the adjacent end wall of the crate, a member mounted on each end wall below the respective depending cleat portion, and a detachable member connecting each depending cleat portion with the end wall member therebelow, to detachably fasten and maintain the cover in position on and closing the crate.

10. An end clip for crate covers, embodying spaced flanges formed to fit over and be attached to the end of a cover, and a portion depending from said flanges for detachable fastening to a crate body.

11. A metal end clip for crate covers, embodying spaced flanges formed to fit over and receive the end of a cover therebetween, and a depending flange portion extending laterally from said end receiving flanges for detachable fastening to a crate body.

12. A metal end clip for crate covers, embodying spaced flanges formed to fit over and receive the end of a crate cover therebetween, and a flange depending from one end of said spaced flanges, the said depending flange formed with a bore therethrough offset from the plane thereof.

13. A metal end cleat for crate covers, embodying spaced flanges formed to fit over and receive the end of a crate cover therebetween, said flanges of a length greater than the width of a cover end to be received therein and forming opposite end portions for bending inwardly against a cover side edge, and a flange depending from said cover receiving flanges for detachable fastening to a crate body.

14. A metal end cleat for crate covers, embodying a cover end receiving portion formed to fit over and be fixed on the end of a cover, and a depending flange portion formed to be detachably fastened to the crate body.

15. As a new article of manufacture, a sheet metal end clip for crate covers, comprising spaced flanges formed to fit over and be fixed to the end of a crate cover, and a depending flange extending laterally from said spaced flanges and provided with a bore therethrough offset laterally from the plane thereof.

16. As a new article of manufacture, a sheet metal end clip for crate covers, comprising spaced flanges to receive and be attached over the end of a crate cover, and

a depending flange extending laterally from one end of said spaced flange, a portion of said depending flange offset laterally from the side thereof opposite said spaced flanges and provided with a bore therethrough.

17. As a new article of manufacture, a sheet metal end cleat for crate covers, composed of a single blank of sheet metal folded longitudinally to provide a double-ply

flange portion having the plys thereof bent laterally to form spaced flanges arranged to fit over and receive the end of a crate cover, said double-ply flange formed for detachable fastening to a crate body.

Signed at Decatur, Macon County, Illinois, this 4th day of March, 1924.

GEORGE H. HAMP.
